RAILWAY TRAFFIC CONTROLLING APPARATUS

Herbert A. Wallace, Edgewood, Pa., assignor to
The Union Switch & Signal Company, Swiss-
vale, Pa., a corporation of Pennsylvania

Application September 17, 1941, Serial No. 411,161

12 Claims. (Cl. 246—219)

My invention relates to railway traffic controlling apparatus, and it has particular reference to the organization of such apparatus into railway traffic controlling systems incorporating means for controlling railway traffic controlling devices or functions such as signals and switches and incorporating means for electrically locking such functions. More particularly, my invention relates to systems of the class named wherein both the traffic controlling functions and the electric locking functions are controlled by using the track rails as transmission conductors, thus obviating the necessity of line wires.

It has been proposed heretofore to control either, but not both, traffic controlling functions or electric locking functions without using line wires by locating the controlling traffic responsive means adjacent either the traffic or the locking function respectively. Approach locking of a track switch and control of the associated distant signal has been attained, for example, by locating the track relay of the approach section at the signal for controlling the signal without line wires, and by extending a line circuit from the signal location to the switch location for controlling the approach locking. Alternately, the approach track relay may be located adjacent the home signal or the track switch location, thereby enabling the approach locking to be effected without line wires, but involving a line wire circuit extending from the relay location to the approach signal at the opposite end of the section to control such signal. Similarly, signal indication locking wherein the proper restrictive indications of distant signals leading up to an interlocking are checked prior to releasing the locking of a signal lever, and traffic locking wherein signal levers controlling traffic in either direction over a single track stretch are locked to prevent the clearing of opposing signals when the stretch is signaled for a traffic movement in one direction, both generally involve the use of line wire circuits to control either the locking or the traffic controlling functions.

An object of my invention is to obviate the necessity for line wire circuits in systems of the above described class, by utilizing the track rails as transmission conductors for effecting the control of both the electric locking and the traffic controlling functions.

Another object is to provide a traffic controlling system in which no line wires are involved in the control of a distant signal and approach locking of the function associated with such signal.

Another object is to provide railway traffic con-

trolling systems in which no line wires are required to establish control of a distant signal, approach locking of a function associated with each signal and remotely located with respect thereto, and approach annunciators or indicators at the remotely located associated function.

Another object is to provide railway traffic controlling systems in which no line wires are involved in approach locking a function and in checking the position of a distant signal associated with such function prior to releasing the locking of the function.

Another object is to incorporate into systems of the above described class utilizing no line wires, approach control of the home signal associated with the approach locked function.

Another object is to provide railway traffic controlling systems wherein traffic locking between two control towers at the opposite ends of a stretch is effected without using line wires by employing the track rails as transmission conductors.

Another object is to provide novel and improved railway traffic controlling systems wherein traffic locking means at two remotely spaced control towers, and indications relating to proposed traffic movements over the controlled stretch intermediate the towers, are controlled without using line wires by utilizing the track rails as transmission conductors.

Another object is to provide novel and improved railway traffic controlling systems incorporating means for providing and utilizing a relatively large number of codes applied to the track rails of a stretch for controlling without using line wires the locking of remotely located functions, the operation and approach control of associated control functions, and the operation of indicators or other devices for conveying information.

Another object is to provide novel and improved railway traffic controlling systems of the above described class provided for a stretch of track and arranged so as to effect control of train-carried apparatus on a train irrespective of the direction of movement of the train over the stretch.

Another object is to provide novel and improved railway traffic controlling systems.

50 The above-mentioned and other important objects and characteristic features of my invention which will become readily apparent from the following description, are attained in accordance with my invention by controlling the locking of a control function located adjacent one end of a

track section by current of a particular character transmitted wholly over a track circuit comprising the rails of the section from a source at the other end of the section, and controlling the operation of an associated control function at the other end of the section by current of a distinctively different character transmitted wholly over a track circuit which also includes the rails of the section and which is supplied with current from a source at the one end of the section.

My invention also resides in the organization and arrangement of apparatus into railway traffic controlling systems involving in various combinations the control of functions, the locking of remotely located associated functions, the control of train-carried apparatus, and approach control of functions and annunciations, as will be made clear in the following description.

I shall describe two forms of apparatus embodying my invention and shall then point out the novel features thereof in claims.

In the accompanying drawings, Fig. 1 is a diagrammatic view illustrating one embodiment of my invention applied to the control of operation and locking of functions associated with a stretch of railway track. Figs. 2a and 2b are diagrammatic views which when placed end to end with Fig. 2a on the left, represent a modified arrangement embodying my invention of the apparatus of Fig. 1. Fig. 3 is a diagrammatic view illustrating a modified arrangement embodying my invention of a portion of the apparatus shown in Fig. 2b. In each of the several views, similar reference characters have been employed to designate corresponding parts.

Referring to Fig. 1, the reference characters 1 and 1a designate the track rails of a stretch of railway track X which is connected to a siding or spur track Y by means of a track switch W, and over which track X traffic normally moves in the eastbound direction as indicated by an associated arrow in the drawings, or from left to right as viewed in the drawings. Track X is divided by the usual insulated joints 2 into a plurality of successive adjoining track sections D—E, E—F and F—G. Sections D—E and E—F will be referred to hereinafter as approach sections, while section F—G in which the switch W is located, will be referred to as a detector section. Each of these sections is provided with a track circuit, the circuits for sections D—E and F—G being provided in the usual manner by connecting a suitable source of track circuit energy, such as a track battery TB, across the rails at one end of the section and connecting a track relay, designated by the reference character TR with a suitably distinguishing suffix, to the rails at the other end of the section. Section E—F is provided with two track circuits formed by supplying to one end of the section coded track circuit current of a distinctive character, by supplying to the other end coded track circuit current having distinctively different characteristics, and by providing each end of the section with a track relay, designated by the reference character TR with a suitably distinguishing suffix, responsive only to current of the character supplied at the opposite end of the section, as will be made clear presently.

Traffic on track X moving in the normal direction is governed by signals SE and SF located respectively at opposite ends of section E—F. These signals may be of any desired type such as position light, color light, semaphore, searchlight, etc., and for the purposes of this description it will be assumed that the signals are of the three-

position semaphore type. Signal SF comprises two signal units U1 and U2 located on a single mast. Each unit U of signal SF is provided with a signal lamp, designated by the reference character L with a suitably distinguishing suffix corresponding to the suffix employed in the reference character of the associated signal unit, which lamps are normally dark but which become energized in a manner to be explained hereinafter upon the approach of a train to the signal. Each unit of signal SF controls an associated circuit controller, designated by the reference character J with a suffix corresponding to the suffix employed in the reference character of the associated signal unit, comprising a contact member 11 operated by the associated signal mechanism and engaging a fixed contact 12 when and only when the associated signal mechanism is in its most restrictive or stop position. Controller J1 also comprises a second movable contact member 13 operated by the associated mechanism of unit U1 into engagement with a fixed contact 14 when unit U1 is in its stop position, and engaging another contact 15 when unit U1 is in either its caution or its clear position. Signal SE comprises a single semaphore unit operating a circuit controller J3 having a movable contact member 16 operated by the signal mechanism into engagement with a contact member 18 when the associated signal mechanism is in its least restrictive or clear condition and into engagement with another contact member 17 when the associated signal mechanism is in or between its restricting or caution and stop positions. Signal SF governs the movement of traffic over switch W and section F—G and will be referred to hereinafter as a home signal, while signal SE governs traffic approaching signal SF and switch W and will be referred to hereinafter as an approach or distant signal.

Signal SF is a semi-automatic signal controlled in the usual manner by traffic conditions in section F—G and by a manually operable control member V, which may, for example, be a signal lever of an interlocking machine. Lever V normally occupies a normal position N, and is operable to a reverse position R wherein it is conditioned to cause the operation of signal unit U1 of signal SF from its stop condition. Suitable locking means, such as, for example, a locking segment 19 secured to lever V and engageable by a locking dog 21, provided for lever V prevents movement of the lever from its reverse position R into its full normal position N unless a lock magnet M is energized to actuate locking dog 21 out of engagement with segment 19. Lever V ordinarily is interlocked with the control lever of the associated switch W in such manner as to permit movement of the switch lever to take place only when lever V is in its full normal position N. This locking may be either mechanical or electrical, and such locking apparatus together with the control apparatus and circuits for controlling switch W are not illustrated since the specific form of such apparatus and circuits forms no part of my present invention and hence have been omitted in order to avoid unduly complicating the drawings by circuits and apparatus well known to the art.

An approach relay AR is provided to control electric lock magnet M and an approach indicator AK. Relay AR is controlled by a circuit which will be pointed out in detail hereinafter.

The rails of section E—F are supplied adjacent end F with current having distinctive characteristics and coded at one code rate or another ac-

cording to the position of unit U1 of signal SF. The coding of this current is effected by means of a suitable code transmitter or coder CTF having a plurality of contact members each operated by the coder at a different code rate. For example, coder CTF is represented as being provided with contact members 75 and 180 operated respectively by the coder at a rate of 75 and 180 times per minute. When unit U1 is at stop, as indicated in the drawings, alternating current of a particular frequency coded at the 75 code rate is supplied to section E—F at its exit end F over a circuit which extends from one terminal of secondary winding 23 of line transformer LTF through condenser 24, contact 75 of coder CTF, contact 14—13 of controller J1 operated by unit U1 of signal SF, and primary winding 25 of track transformer TTF to the other terminal of winding 23 through a common connection indicated by the reference character CC. Secondary winding 26 of track transformer TTF is connected to the rails of section E—F adjacent its exit end F, and primary winding 22 of line transformer LTF is connected as by wires 27 and 28 to a suitable source of alternating current, such as a generator, not shown, supplying line wires 27 and 28 with current having a particular frequency of, say, 100 cycles per second, and, it follows, therefore, that the rails of section E—F are normally supplied at end F with 100 cycle current coded at the 75 code rate. When signal unit U1 is in either its caution or its clear position, contact 13—14 of controller J1 is opened and contact 13—15 of controller J1 is closed to connect secondary winding 23 of transformer LTF to transformer TTF through contact 180 of coder CTF so that 100 cycle current coded at the 180 code rate is supplied to the rails of section E—F. The condenser 24 preferably is utilized to tune the circuit connection of transformer LTF to transformer TTF to effective resonance at the frequency of 100 cycles per second.

Relay TRE is connected to the rails at the entrance end E of section E—F through a transformer RTE which has its primary winding 30 connected to the track rails and has its secondary winding 31 connected through a condenser 33 and a rectifier 32 to the winding of relay TRE. The capacity of condenser 33 is selected with respect to the constants of the winding of relay TRE and secondary 31 of transformer RTE in such manner that the connection of the relay to the transformer is tuned to effective resonance only at the frequency corresponding to the frequency of current supplied to the rails at the opposite end E of the section, hence relay TRE is effectively energized and responds only to the 100 cycle current supplied to section E—F at its exit end F.

Two decoding relays, designated by the reference characters HE and AJE, are associated with and are controlled by relay TRE through the medium of a decoding transformer DTE and a decoding unit DU180. The decoding transformer comprises a secondary winding 35 inductively coupled with a primary winding 34, a portion of which is connected through a center-tapped connection to one terminal C of a suitable source of unidirectional current, such as a battery not shown but having its opposite terminals designated by the reference characters B and C, and the opposite ends of such portion are connected alternately to the other terminal B of this source according as relay TRE is picked up to close its front contact 36 or is released to close its back contact 37. It is readily apparent that when

relay TRE follows code, primary winding 34 of transformer DTE is supplied with unidirectional current in such manner as to cause an alternating current having a frequency corresponding to the code rate of operation of relay TRE to be induced in secondary winding 35. This secondary winding is connected through a mid terminal connection to one terminal of relay HE and has its opposite ends connected alternately to the other terminal of relay HE according as relay TRE operates its contact members to close its front contact 38 or its back contact 39, respectively, and it follows that when relay TRE operates, the alternating current caused to be induced in winding 35 is supplied to relay HE as substantially unidirectional current. Relay HE is proportioned to be picked up when relay TRE responds to current coded at either the 75 or the 180 code rate received from the rails of section E—F.

Relay AJE is connected to primary winding 34 of transformer DTE through decoding unit DU180, the details of construction of which are not shown in the drawings but which usually comprises a rectifier and a reactor condenser tuning unit tuned to resonance at a frequency corresponding to the 180 code rate whereby relay AJE is effectively energized and picked up when and only when relay TRE responds to 180 code received from the rails of section E—F.

Relays HE and AJE cooperate in the usual manner to control signal SE by circuits which have been omitted from the drawings since they are well known. It is deemed sufficient to state that when relays HE and AJE are both picked up, signal SE is caused to display its clear indication; when relay AJE is released and relay HE is picked up, signal SE is caused to display its caution indication; and when both relays HE and AJE are released, signal SE is caused to display its stop indication.

When section D—E is unoccupied so that relay TRD is picked up, the rails of section E—F are supplied at the entrance end E with current having characteristics distinctively different from the characteristics of the current supplied to the opposite end of the section. Such differently characterized current supplied at E to section E—F may comprise, for example, alternating current having a frequency distinctively different from the frequency of the current supplied at the opposite end F of the section, and having a code rate determined according to the position of signal SE and the occupancy of section D—E. Current of a frequency distinctively different from the 100 cycle current supplied to end F of section E—F, may be obtained from any suitable source, such as a generator of current having a distinctive frequency different from the 100 cycle current, or as shown may be obtained from a frequency changer FC comprising a transformer FT having a secondary winding 42 inductively coupled with a primary winding 41 supplied through a full wave rectifier 40 with alternating current from the secondary winding 23 of a line transformer LTE. The primary winding 22 of transformer LTE is connected to a suitable source of alternating current, such as line wires 27 and 28, and it is readily apparent that rectifier 40 when energized by 100 cycle current supplies to winding 41 of transformer FT two pulses of unidirectional current in each cycle of alternating current, hence there is induced in secondary winding 42 of transformer FT by these double

frequency pulses of unidirectional current in winding 41, an alternating electromotive force having a frequency which is double the frequency of the 100 cycle current supplied to rectifier 40. It follows, therefore, that secondary winding 42 of transformer FT may be considered as a source of alternating current having a frequency of 200 cycles per second, or a frequency distinctively different from the frequency of the 100 cycle current supplied at end F to section E—F.

When signal SE is in either its stop or its caution position and section D—E is unoccupied, contact 16—17 of the associated circuit controller J3 is closed and 200 cycle current coded at the 180 code rate is supplied at end E to the rails of section E—F over a circuit extending from one terminal of winding 42 of transformer FT through condenser 43, front contact 44 of relay TRD, contact 180 of a code transmitter CTE, contact 17—16 of controller J3, primary winding 25 of transformer TTE which has its secondary winding 26 connected to the rails at entrance end E of section E—F, and a common connection, indicated by the reference character CC, to the other terminal of winding 42. When section D—E is unoccupied and signal SE is in its clear position so that contact 16—18 of controller J3 is closed, 200 cycle current coded at the 75 code rate is supplied to section E—F at end E over a circuit which corresponds to the circuit over which 200 cycle current coded at 180 code is supplied to transformer TTE, except that contact 16—18 of controller J3 and contact 75 of coder CTE replace contacts 16—17 of controller J3 and contact 180 of coder CTE, respectively. Coder CTE as shown is provided with a contact 20 operated at a rate of 20 times per minute, and when relay TRD is released due to a train in section D—E, 200 cycle current coded at the 20 code rate is supplied to transformer TTE over a circuit including back contact 48 of relay TRD and contact 20 of coder CTE, as is readily apparent from an inspection of the drawings. Condenser 43 is provided in the circuit connection of transformer FT to transformer TTE to tune the circuit connection to effective resonance at the frequency of 200 cycles per second.

Relay TRF is connected to the rails at exit end F of section E—F through a receiving transformer RTF which has its primary winding 30 connected to the rails of section E—F and has a secondary winding 31 connected through a condenser 50 and a rectifier 32 to relay TRF. Condenser 50 is selected with respect to the constants of the winding of relay TRF and winding 31 of transformer RTF so as to tune the circuit connection of the relay and transformer to effective resonance at a frequency corresponding to the frequency of the current supplied to the rails at the opposite end E of the section, and relay TRF accordingly is effectively energized in response only to the 200 cycle current supplied at entrance end E of the section.

Decoding relays HF and AJF are associated with and are controlled by relay TRF through a decoding transformer DTF in a manner substantially corresponding to the manner explained in detail heretofore whereby relays HE and AJE are controlled by relay TRE. In addition, transformer DTF has associated therewith another or slow code detecting relay BSA and a relay FSA. Relay FSA is arranged with its winding interposed in the circuit connection of front contact 36 of relay TRF to a portion of primary winding 34 of transformer DTF, and relay FSA when en-

ergized closes its front contact 51 to complete an obvious circuit including relay BSA and over which another portion of winding 34 of transformer DTF is energized when back contact 37 of relay TRF is closed. The relays FSA and BSA are preferably sufficiently slow releasing to bridge respectively the "off" and "on" intervals of 20 code energy, hence when relay TRF operates at the 20 code rate, relay FSA is energized each time relay TRF closes its front contact 36 in response to an "on" interval of code energy received from the rails of the section, and with front contact 51 of relay FSA closed, relay BSA is energized each time relay TRF closes its back contact 37 in response to an "off" interval of code in the associated section. When, however, relay TRF is steadily energized, relay BSA is released since its energizing circuit is then held open at back contact 37 of relay TRF, or if relay TRF is steadily released, both relays FSA and BSA are released since relay FSA is deenergized when its energizing circuit is held open at front contact 36 of relay TRF and with contact 51 of relay FSA open, relay BSA is likewise deenergized. It follows, therefore, that relay BSA is energized when and only when its associated track relay TRF operates in response to coded energy received from its associated section, and by properly proportioning the release periods of relays FSA and BSA, relay BSA may be employed to detect operation of its associated track relay TRF in response to energy coded at the rate of 20 or more code cycles per minute. Relay BSA, as will be made clear presently, controls the approach lighting of lamps L1 and L2 of signal SF, by at times energizing the lamps over an obvious circuit including back contact 52 of relay BSA.

When relay TRF responds to either 75 or 180 code current from section E—F, relay HF is effectively energized and picked up to close its front contact 53 and thereby complete an obvious circuit for approach relay AR. Relay AR controls an approach indicator AK over its front contact 54.

When relay TRF responds to 180 code from section E—F and units U1 and U2 of signal SF are both at stop so that contacts 11—12 of circuit controllers J1 and J2 are respectively closed, magnet M of the electric locking apparatus of lever V is energized over a normal circuit extending from terminal B through front contact 53 of relay HF, front contact 56 of relay AJF, contact 11—12 of controller J2, contact 11—12 of controller J1, front contact 57 of relay AR and the winding of magnet M to terminal C. If relay AR is released, magnet M may be energized over either of two alternate circuits, one of which I shall term a track circuit release circuit which is completed when relay TRG is released and extends from terminal B through back contact 59 of relay TRG, contacts 11—12 of controllers J2 and J1, respectively, back contact 60 of relay TRG and the winding of magnet M to terminal C; and the other alternate circuit I shall term a time release circuit completed at the end of a predetermined time delay required to operate to a closed position contacts 61 and 62 of a time release device TD, which may, for example, be a time element relay, or as shown, a manually operated time release. This time release circuit extends from terminal B through contact 61 of time release device TD, contacts 11—12 of controllers J2 and J1, respectively, contact 62 of

time release device TD and the winding of magnet M to terminal C.

As indicated in the drawings, unit U1 of signal SF is provided with an energizing circuit controlled by traffic conditions in the stretch (this control being indicated conventionally by the representation of traffic controlled contact 65), and including contact 66 of lever V closed in the reverse position of the lever and contact 67 closed in the normal position of time release TD.

The apparatus of Fig. 1 is in its normal condition, as represented in Fig. 1, when sections D—E, E—F and F—G are unoccupied, and units U1 and U2 of signal SF are at stop. In this condition of the apparatus, 100 cycle current coded at the 75 code rate is supplied to the rails of section E—F at its exit end F in a manner previously described, and relay TRE responds to such current to hold relay HE energized and relay AJE released so that signal SE is in its caution position. With signal SE at caution, 200 cycle current coded at the 180 code rate is supplied to the rails of section E—F at entrance end E, as previously mentioned, and relay TRF in response to such current holds relays BSA, FSA, HF and AJF energized. Approach relay AR accordingly is energized, approach indicator AK is illuminated, and lock magnet M of lever V also is energized.

When lever V is operated to clear unit U1 of signal SF, contacts 11—12 and 13—14 of controller J1 are opened in response to the clearing of unit U1. The previously traced normal circuit of lock magnet M is opened when contact 11—12 of controller J1 opens, and as a result magnet M releases to render effective the electric locking of lever V. When unit U1 clears, contact 13—15 of controller J1 is also caused to close and shift the coding of the 100 cycle current from the 75 code rate to the 180 code rate, as explained previously. Relay TRE accordingly causes both relays HE and AJE to be energized in response to the 180 code rate received from the rails of section E—F, and signal SE is controlled to its clear position, thereby causing controller J3 to open contact 16—17 and close contact 16—18 so that the coding of the 200 cycle current supplied to section E—F at E is shifted from the 180 code rate to the 75 code rate. At the opposite end of section E—F, relay TRF responds to the 200 cycle current coded at the 75 code rate, and relays HF, FSA and BSA are energized but relay AJF is released.

If, now, the operator moves lever V towards its normal position prior to a train entering section D—E, unit U1 of signal SF is restored to its stop position, but the lever is prevented by the electric locking from occupying its full normal position N at this time so that operation of switch W cannot be effected. However, when unit U1 goes to stop, contact 11—12 of controller J1 closes to shift the coding of the 100 cycle current supplied at end F of section E—F from the 180 code rate to the 75 code rate, and relay AJE at entrance end E of the section accordingly drops in response to relay TRE following the 100 cycle current coded at the 75 code rate. Signal SE accordingly is operated to its caution position, and contact 16—17 of controller J3 closes so that the 200 cycle current supplied to end E of section E—F is coded at the 180 code rate. This 200 cycle 180 code current causes relay TRF to operate and energize all the associated decoding relays AJF, HF, FSA and BSA, and electric lock magnet M accordingly becomes

energized over its previously traced normal circuit to actuate locking dog 21 from engagement with locking segment 19, thereby permitting lever V to be restored to its full normal position N and conditioning the apparatus to permit an operation of switch W. It is to be noted that lock magnet M is energized to release the locking of lever V, only if signal SE goes to caution to alter the code rate of a 200 cycle current from the 75 to the 180 code rate. The releasing of the locking of lever V indicates that distant signal SE is displaying the proper restrictive indication, and it follows that the apparatus of Fig. 1 effects signal indication locking wherein the proper restrictive indication of a distant signal is checked prior to releasing the locking of the control lever of the associated home signal.

If, with lever V in its reverse position R to clear unit U1 of signal SF, and with signal SE cleared so that 200 cycle current coded at the 75 code rate is supplied to the rails of section E—F with the result that relays HF, FSA and BSA are energized but relay AJF is released and lock magnet M also is released, a train enters approach section D—E, the releasing of the associated track relay TRD prevents a release of the electric locking over its normal circuit in the manner above described, and the rails at the entrance end E of section E—F are supplied with 200 cycle current coded at the 20 code rate over a circuit previously traced and including back contact 48 of relay TRD and contact 20 of coder CTE. Relay HF accordingly releases due to relay TRF following the 20 code 200 cycle current, with the result that approach relay AR also releases to interrupt the energization of indicator AK. Indicator AK thereupon becomes dark to indicate that a train is approaching signal SF within the limits of sections D—E and E—F. Relays FSA and BSA, however, remain energized and the signal lamps of signal SF remain dark.

In the event that, with the apparatus in the condition just described, lever V is operated toward its normal position N, unit U1 of signal SF goes to stop but the lever is prevented by locking dog 21 engaging segment 19 from occupying its full normal position. When unit U1 goes to stop, the 100 cycle current supplied to section E—F is shifted from the 180 to the 75 code rate, and signal SE accordingly is controlled to its caution position. With relay TRD released, however, the code rate of the 200 cycle current supplied to section E—F is not affected by the change in position of signal SE, so that relays AJF and HF remain released to retain approach relay AR and lock magnet M released. Lever V accordingly remains locked out of its normal position N, but may be restored to its normal position by operating the time release device TD. At the end of the predetermined time interval of this release, contacts 61 and 62 become closed to complete the previously mentioned time release circuit for lock magnet M, which circuit includes contacts 61 and 62 and contacts 11—12 of controllers J1 and J2, respectively. Magnet M accordingly becomes energized to actuate locking dog 21 and unlock the lever to permit it to be operated to its full normal position, and it follows, therefore, that when a train occupies an approach section, a time release of the locking of lever V may be effected at the expiration of a predetermined time delay enforced by a time release device.

When a train occupies section E—F, both relays TRE and TRF are shunted and all decoding relays associated therewith are released. Sig-

nal SE is controlled to its stop position, while the lamps L1 and L2 of signal SF are illuminated due to relay BSA closing its back contact 52. The lamps of signal SF accordingly are approach energized by the apparatus of Fig. 1 when a train occupies section E—F.

With the train in section E—F, it is, of course, obvious that with lever V in its reverse position and unit U1 of signal SF cleared, the operator may restore signal SF to its stop position and may restore lever V to its full normal position by moving lever V toward its normal position and by operating the time release device TD. At the end of the predetermined time interval of release TD, magnet M becomes energized to unlock lever V in the manner pointed out in detail heretofore.

In the event, however, that signal SF is cleared and the train accepts the clear indication and enters section F—G, relay TRG is shunted and releases to set unit U1 of signal SF to stop and to effect a track circuit release of the locking of lever V over a circuit previously traced and including back contacts 59 and 60 of relay TRG and contacts 11—12 of controllers J1 and J2, respectively. The operator may now restore lever V to its full normal position N and it follows that the locking of lever V is automatically released when the train enters the section governed by the signal controlled by such lever.

Signal SE goes to caution when the train vacates section E—F since the 100 cycle current supplied to section E—F at end F is coded at the 75 code rate when unit U1 is at stop, hence relay TRE operates to energize decoding relay HE but not AJE. The apparatus of Fig. 1 of course is restored to normal when the train vacates section F—G and relay TRE picks up.

From the foregoing description, it is readily apparent that the apparatus embodying my invention provides means whereby control of one function and approach locking of another remotely located function, are effected by utilizing the track rails as transmission conductors, thereby obviating the necessity of pole line or auxiliary wires along the track. Also, it is apparent that such control and approach locking of these remotely spaced functions are incorporated into a system which also provides approach control of one of the functions and signal indication locking of the other function.

Figs. 2a and 2b, when placed end to end with Fig. 2a on the left, represent a system which I shall refer to hereinafter as being shown in Fig. 2, wherein the apparatus of Fig. 1 is represented modified to provide traffic locking between two control points or towers P and Q at opposite ends of a stretch of single track X connected at its right-hand end, as viewed in the drawings, by switch W1 to a siding track Y and connected at its left-hand end by switch W2 to a siding track Z. The rails 1 and 1a of track X are divided by insulated joints 2 to form a track section E—F extending from adjacent tower P to adjacent tower Q, while detector track sections D—E and F—G are provided for switches W2 and W1, respectively, by interposing insulated joints 2 in rails 1 and 1a at the opposite ends of stretch X.

Section E—F is provided with a track circuit which substantially corresponds to the track circuit of section E—F of Fig. 1, and which differs from the track circuit of section E—F of Fig. 1 in that relay TRE of Fig. 2a is conditioned to respond to either 200 or 100 cycle current ac-

cording as a traffic lever V8, to be referred to later, is in its respective normal or reverse position, and relay TRF of Fig. 2b is similarly conditioned to respond to either 100 or 200 cycle current according as another traffic lever V3 is in its normal or reverse position. The detector sections D—E and F—G are also provided with track circuits, which include relays TRD and TRG, respectively. These track circuits have been represented for simplicity as being of the usual type comprising a source of current at one end and a track relay at the opposite end, but it is to be understood, of course, that such circuits may be arranged in a manner corresponding to that of section E—F, and which arrangement, as will be made clear presently, is particularly effective for controlling apparatus on a train irrespective of the direction of the train movement.

Each end of section E—F is provided with a source of 100 cycle current and a source of 200 cycle current. The 100 cycle current may be derived from line wires 27 and 28, and the 200 cycle current may be derived from frequency changers FC corresponding in construction to the frequency changer FC illustrated and described in connection with the apparatus of Fig. 1.

Eastbound traffic operating over track X from left to right as viewed in the drawings is controlled by a distant signal ESE disposed adjacent end E and by a home signal ESF at end F of section E—F. Westbound traffic on track X is governed by a distant signal WSF at end F and a home signal WSE at end E of section E—F. The distant signals ESE and WSF, and home signals ESF and WSE, preferably correspond respectively to the distant and home signals SE and SF shown in Fig. 1 and described heretofore; and each signal unit shown in Fig. 2 is preferably provided with a circuit controller designated by the reference character J with a suitably distinguishing suffix.

Home signals ESF and WSE are semi-automatic signals controlled by traffic conditions on track X and by control levers V1 and V6, respectively, in a manner corresponding to that mentioned heretofore whereby signal SF is controlled by the apparatus of Fig. 1. Distant signal WSF at F is controlled by the track circuit apparatus of section E—F and by a signal control lever V2, while distant signal ESE at E is controlled by the track circuit apparatus of section E—F and by a signal control lever V5, as will be made clear presently.

Signal control levers V1 and V2 are incorporated into interlocking apparatus located at tower Q and have associated therewith traffic levers V3 and V4, while signal control levers V5 and V6 are incorporated into interlocking apparatus at tower P and have associated therewith traffic levers V7 and V8. In accordance with the usual practice, the interlocking apparatus at tower Q is provided with locking means arranged as indicated by the chart represented in Fig. 2b in such a manner that when lever V2 is in its reverse position R, lever V3 is locked in its normal position N and lever V4 is locked in its reverse position R, and when lever V3 is in its reverse position R, lever V4 is locked in its normal position N. In like manner, the interlocking apparatus at tower P is arranged as indicated by a chart represented in Fig. 2a in such manner that when lever V6 is in its reverse position R, lever V7 is locked in its normal position N and lever V8 is locked in its reverse position R, while

when lever V1 is in its reverse position lever V8 is locked in its normal position.

An electric locking magnet M1 and an approach relay AR1 are associated with lever V1 of Fig. 2b, and a lock magnet M2 and an approach relay AR2 are associated with lever V5 of Fig. 2a, in a manner substantially corresponding to the association of lock magnet M and approach relay AR with lever V of Fig. 1.

Each lever V shown in Fig. 2 is provided with contacts selectively closed in accordance with the position occupied by the lever, and each contact of the lever bears the reference character N or R to designate the position of the associated lever in which such contact is closed. For convenience in tracing circuits, the contacts of the levers have been represented in the drawings remote from the levers controlling such contacts, but each of such contacts has been designated by the reference character of the associated control lever, by a reference character individual to such contact, and by the reference character N or R to indicate the position of the associated lever at which the contact is closed. For example, lever contact 85 bears the reference characters N and V8 to indicate that this contact is controlled by lever V8 and is closed only when such lever is in its normal position N, while lever contact 86 bears the reference characters R and V8 to indicate that this contact is closed only when lever V8 is in its reverse position R.

Similarly, to facilitate tracing circuits, contacts of certain relays are represented in Figs. 2a and 2b disposed remote from the relays operating such contacts, but each of such contacts has been represented in its normal position and bears the reference character of the associated relay operating such contact as well as a reference character individual to such contact. Thus, back contact 59 bears the reference character TRG and is represented in its open position to indicate that such contact is controlled by relay TRG and is normally open.

The coders CTE and CTF of Fig. 2 are similar to coders CTE and CTF of Fig. 1, except that in Fig. 2 coder CTF is provided with an additional coding member 20 operated at a rate of 20 times per minute, and coder CTE is provided with an additional coding member 120 operated at the rate of 120 times per minute. Coder CTE has associated therewith additional coding apparatus capable of providing relatively low code rates of the order of 20, 17 and 15 cycles per second. Such additional coding apparatus may comprise a motor operated device having a plurality of contact members operated respectively at the several relatively low code rates, or as shown may comprise a plurality of code generating and code disconnecting relays, designated respectively by the reference characters CG and CD with suitably distinguishing suffixes, arranged in a manner explained hereinafter to interrupt or code current in a circuit at a rate of 20, 17 or 15 times per minute.

The decoding apparatus associated with relays TRE and TRF of Figs. 2a and 2b substantially correspond to the similar apparatus shown provided for relays TRF and TRE, respectively, of Fig. 1, except that in Fig. 2 the decoding apparatus associated with relay TRF incorporates an additional decoding relay, designated by the reference character BJF, connected through a decoding unit DU120 to the associated decoding transformer DTF. The details of construction of decoding unit DU120 are similar to those here-

tofore mentioned for decoding unit DU120, except that unit DU120 is tuned to resonance at a frequency corresponding to the 120 code rate, hence each relay BJ is energized when and only when the associated track relay responds to current coded at a rate of substantially 120 cycles per minute. As shown, a portion of the decoding apparatus associated with track relay TRF is controlled by contacts 80 and 81 of levers V4 and V3, respectively, so that such decoding apparatus is non-responsive to operation of the associated relay TRF unless either lever V4 or V3 is in its reverse position.

The decoding apparatus associated with relay TRF additionally includes other decoding means responsive to the previously mentioned relatively low code rates of the order of 20, 17 and 15 cycles per minute. Such additional decoding apparatus comprises a slow pick-up relay C1R, a plurality of slow releasing code selecting relays at least one for each of said relatively low code rates and each designated by the reference character CS with a suitably distinguishing prefix, and a plurality of code registering or detecting relays one for each code rate and each designated by the reference character CR with a suitably distinguishing prefix. The arrangement and manner of operation of the additional decoding apparatus associated with relay TRF will be explained in detail presently, but at this time it should be pointed out that such apparatus is conditioned to be active only when both traffic levers V3 and V4 occupy their normal positions so that contacts 82 and 83 of levers V3 and V4, respectively, are closed. It should also be noted that both the code registering relays CR and the decoding relays associated with the decoding transformer DTF, are effective to control lock magnet M1 of lever V1, and the approach relay AR1, in a manner substantially corresponding to the manner that magnet M and relay AR are controlled by the apparatus of Fig. 1.

Associated with the decoding apparatus of relays TRE and TRF are two indicators, designated respectively by the reference characters K and VK with distinguishing suffixes corresponding to the suffix of the associated track relay. The manner of control and the function of such indicators will be pointed out hereinafter.

Each control station or tower is additionally provided with a manually operable circuit controller, such as a push button PB1 or PB2 shown provided for stations Q or P, as the case may be. The functions of these push buttons will be explained hereinafter.

The apparatus represented in Fig. 2 is in its normal condition, as represented in the drawings, when sections D-E, E-F and F-G are unoccupied, levers V all occupy their normal positions, and all signals are at stop.

In this normal condition of the apparatus, contact 85 of lever V8 is closed so that relay TRE is conditioned by condenser 50 to respond to 200 cycle current, while contact 87 of lever V3 is closed and as a result relay TRF is conditioned by condenser 33 to respond to 100 cycle current. Current having a frequency of 200 cycles and a code rate of 180 is supplied to the rails of section E-F at end F over a circuit extending from one terminal of secondary winding 42 of transformer FT of frequency changer FC through condenser 43, normal contact 89 of lever V3, normally closed contact 91 of push button PB1, contact 180 of coder CTF, contact 17-16 of circuit controller J3F operated by signal WSF, front contact 92 of

relay TRG, normal contact 93 of lever V3, primary winding 25 of track transformer TTF and through a common connection, indicated by the reference character CC, to the other terminal of winding 42. Relay TRE operates in response to this current and all decoding relays associated therewith are energized, as represented in Fig. 2a. Approach relay AR2, indicator AKE, and lock magnet M2 associated with lever V5 at tower P accordingly are energized, as is readily apparent from an inspection of the drawings, but indicators KE and VKE are deenergized.

At end E of section E-F, 100 cycle current coded at the relatively low code rates of 20 and 17 cycles per minute successively, is supplied to 15 the rails of section E-F over a circuit extending from one terminal of secondary winding 23 of line transformer LTE through condenser 24, back contacts 95, 96 and 97 of code generating relays CG20, CG17 and CG15, respectively, normal contacts 98 and 99 of levers V1 and V8, respectively, and primary winding 25 of track transformer TTE through a common connection indicated by the reference character CC to the other terminal of winding 23. This coding of the 100 cycle current is effected by the code generating relays CG in the following manner.

Referring to Fig. 2a, the code generating relays CG are shown all deenergized, and the circuit for a first slow release code generating relay CG20 is represented completed and extends from terminal B through normal contacts 100 and 101 of levers V1 and V8, respectively, front contact 102 of relay TRD, back contact 103 of code disconnecting relay CD20, the winding of relay CG20, back contact 104 of relay CD17, back contact 105 of relay CG17, back contact 106 of relay CD15 and back contact 107 of relay CG15 to terminal C. Relay CG20 accordingly picks up to open its back contact 95 interposed in the circuit over which 100 cycle current is supplied to transformer TTE, thereby interrupting or coding such current, and relay CG20 also closes its front contact 108 to complete an obvious circuit for relay CD20. Relay CD20 picks up at the end of its slow pick-up period, closing its front contacts 109 and 110 but opening its back contact 103 to deenergize relay CG20, which latter relay drops at the end of its slow release period. To accord with the heretofore assumed code of 20 cycles per minute, the slow acting periods of relays CG20 and CD20 are selected so that the slow pick-up period of relay CD20 and the slow release period of relay CG20 together approximate 3 seconds, hence it follows that relay CG20 when energized remains picked up to hold open for approximately 3 seconds the circuit supplying 100 cycle current to transformer TTE. When relay CG20 drops, its back contact 95 closes to complete the circuit over which transformer TTE is supplied with current. Back contact 111 of relay CG20 also closes to complete a circuit for relay CG17 extending from terminal B through back contact 111 of relay CG20, front contact 109 of relay CD20 (held closed during the slow release interval of this relay), contact 112-113 of circuit controller J3E operated by signal ESE, back contact 115 of relay CD17, the winding of relay CG17, back contact 106 of relay CD15 and back contact 107 of relay CG15 to terminal C. Relay CG17 thereupon picks up to open its back contact 96 and interrupt or code the current supplied to transformer TTE, and front contact 116 closes to complete an obvious circuit for relay CD17. Relay CD17 picks up at the end of

its slow pick-up period, opening its back contact 115 to interrupt the energization of relay CG17, and closing its front contact 117 to complete for relay CD20 a stick circuit extending from terminal B through front contact 116 of relay CG17, front contact 117 of relay CD17, contact 118-119 of controller J3E operated by signal ESE, and front contact 110 and the winding of relay CD20 to terminal C. At the end of its slow release period, relay CG17 releases to close its back contact 96 and thus complete the circuit of transformer TTE which accordingly becomes energized. The slow acting characteristics of relays CG17 and CD17 are selected so that the slow pick-up period of relay CD17 and the slow release interval of relay CG17 when added together approximate 3.5 seconds.

When relay CG17 drops, its front contact 116 opens to open the previously mentioned energizing circuits of relays CD20 and CD17, and at the expiration of their slow release periods, these relays drop to restore the additional coding apparatus to the condition illustrated in the drawing, whereupon the apparatus starts another cycle of coding due to the energization of relay CG20. This operation of the relays continues as long as levers V1 and V8 are in their respective normal positions, relay TRD is energized, signal ESE is at stop, and push button PB2 is unactuated.

It is readily apparent, therefore, that when the additional coding apparatus operates in the manner just described, the circuit of transformer TTE is opened for approximately 3 seconds when relay CG20 is picked up, is momentarily closed when relay CG20 drops, is open for approximately 3.5 seconds when relay CG17 is picked up, and is closed until relays CD20 and CD17 drop at the end of their slow release intervals to restore the apparatus to normal and enable relay CG20 to pick up and initiate another cycle of coding. Under such conditions transformer TTE is supplied with a first pulse of current followed by a 3 second interval when no current flows, and a second pulse of current followed by 3½ second interval when no current flows, and this coding of the current is cyclically repeated. I shall term this type of coding as comprising a combination 20-17 cycle code, in that the coding includes 40 pulses of current which occur at 3 second intervals (or 20 pulses per minute) and pulses of current which occur at 3.5 second intervals (or approximately 17 pulses per minute).

From an inspection of the drawings, it is readily apparent that if push button PB2 is actuated when levers V1 and V8 are in their normal positions, relay TRD is energized and signal ESE is at stop to close contacts 112-113 and 118-119, then the current supplied to transformer TTE is coded at a combination code comprising successive intervals of 20, 17 and 15 code rates. This coding occurs since with push button PB2 actuated to close contact 123, relay CG15 becomes energized when relay CG17 drops, and relay CG15 accordingly picks up to energize relay CD15 and hold relays CD17 and CD20 energized. Relay CG15 picks up when relay CG17 drops, over a circuit extending from terminal B through back contact 124 of relay CG17, front contact 125 of relay CD17, contact 123 of push button PB2, back contact 126 of relay CD15, and the winding of relay CG15 to terminal C. Relay CG15 in picking up opens its back contact 97 to open the circuit over which current is supplied to transformer TTE, and also closes its front contact 127 to en-

ergize relay CD15. Relay CD15 thereupon picks up at the end of its slow pick-up period to close its front contact 128, whereupon relay CD17 becomes energized over a stick circuit extending from terminal B through front contact 127 of relay CG15, front contact 128 of relay CD15, front contact 129 of relay CD17 and the winding of relay CD17 to terminal C. Relay CD20 also becomes energized over a stick circuit connected in multiple with relay CD17 and extending from contact 129 of relay CD17 through contact 117 of relay CD17, contact 118-119 of circuit controller J3E, and front contact 110 and the winding of relay CD20 to terminal C. The energization of relay CG15, however, is interrupted at back contact 126 of relay CD15 when the latter relay picks up, and relay CG15 drops at the end of its slow release interval to close its back contact 97 and thereby complete the previously traced circuit of transformer TTE. The slow acting characteristics of relays CG15 and CD15 are selected so that the slow pick-up period of relay CD15 when added to the slow release period of relay CG15 approximates 4 seconds. It is readily apparent, therefore, that when relay CG15 is picked up, the circuit of transformer TTE is held open for 4 seconds. When relay CG15 drops at the end of its slow release interval, relays CD15, CD17 and CD20 all become deenergized and these relays release at the end of their respective slow release intervals to condition the apparatus to reenergize relay CG20 and initiate another cycle of operation of the coding apparatus. It follows, therefore, that if push button PB2 is held down when signal ESE is at stop and relay TRD is energized, transformer TTE is supplied with a first pulse of current followed by a 3 second off interval when relay CG20 is picked up, a second pulse of current followed by a 3½ second off interval when relay CG17 is picked up, and a third pulse of current followed by a 4 second off interval when relay CG15 is picked up; and that this coding of current which I shall term a combination code of 20, 17 and 15 cycles, is cyclically repeated.

Other codes and combinations of codes are provided by the coding apparatus above described, as is readily apparent from an inspection of the drawings. For example, with relay TRD picked up and signal ESE at its clear position to open contact 112-113 and close contact 112-114, the current supplied to transformer TTE is coded at the 20 code rate only if push button PB2 is unactuated, or at a combination of the 20 and 15 code rates if push button PB2 is actuated to close contact 123. Similarly, if relay TRD is released and signal ESE is at its stop position to close contact 112-113, current supplied to transformer TTE is coded at only the 17 code rate if push button PB2 is unactuated, or at a combination of the 17 and 15 code rates if push button PB2 is actuated to close contact 123. On the other hand, with signal ESE cleared to close contact 112-114 and with relay TRD released, current coded at the 15 code rate only will be supplied to transformer TTE if push button PB2 is actuated to close contact 123. It follows, therefore, that when relay TRD is picked up, the current supplied to transformer TTE will be coded at the 20 code rate or at a combination code including the 20 code rate; if signal ESE is at stop to close contact 112-113, the current will be coded at the 17 code rate or at a combination code including the 17 code rate; while if push button

PB2 is actuated to close contact 123 the coding of the current will include the 15 code rate.

These relatively low rates of coding the current supplied at end E of section E-F are detected at the other end of the section by the code selecting relays CS and code registering relays CR. When the apparatus is in its normal condition as illustrated in Fig. 2 wherein 100 cycle current coded at a combination code of 20 and 17 code rates is supplied to section E-F at end E, relay TRF responds to each pulse of current by picking up during the interval such current flows and releasing when the current flow ceases. For example, when relay TRF responds to a combined 20-17 code, it is energized when the code generating relays CG are released to complete the circuit of transformer TTE, and front contact 132 of relay TRF closes to complete for relay 20CS an energizing circuit extending from terminal B through normal contacts 82 and 83 of levers V3 and V4, respectively, front contact 132 of relay TRF, back contact 133 of relay CIR and the winding of relay 20CS to terminal C. Relay 20CS accordingly picks up to close its front contact 134 and connect the winding of relay CIR in multiple with the winding of relay 20CS. Relay CIR is slow in picking up, while relay 20CS is slow in releasing, the slow acting characteristics of these relays being selected in such manner that the slow release period of relay 20CS and the slow pick-up period of relay CIR add up to approximately 3 seconds. When relay CIR picks up at the end of its slow pick-up period to open its back contact 133, relay 20CS is deenergized but remains picked up due to its slow release characteristics.

With relay 20CS picked up, relays 17CS, 15CS and 13CS also are picked up in sequence over front contacts 135, 136 and 137 of relays 20CS, 17CS and 15CS, respectively. Each relay 17CS, 15CS and 13CS preferably is provided with slow releasing characteristics which hold each of such relays picked up for substantially ½ second after it is deenergized.

At the end of the on period of current, that is, when code generating relay CG20 picks up, relays TRF and CIR release. During the 3 seconds off interval of the code that results due to the energization of relay CG20, relay 20CS releases to open its front contact 134 and close its back contact 141. Relay CG20, however, releases to complete the circuit of transformer TTE prior to relay 17CS releasing, so that when relay TRF picks up due to the on period of current following the 3 second off interval, code registering relay 20CR is energized over a circuit extending from terminal B through normal contacts 82 and 83 of levers V3 and V4, respectively, front contact 132 of relay TRF, back contact 133 of relay CIR, front contact 138 of relay 13CS, front contact 139 of relay 15CS, front contact 140 of relay 17CS, back contact 141 of relay 20CS and the winding of relay 20CR to terminal C. Also, relay 20CS is picked up to recomplete the circuit of relay CIR, and to cause relay CIR to be reenergized and picked up. Relay 20CR is deenergized when relay 20CS picks up to open its back contact 141, but relay 20CR remains up due to its slow releasing characteristics which are selected to provide substantially a 12 second retardation of the release of the relay.

When code generating relay CG17 picks up, relays TRF and CIR drop, and during the 3½ second interval that relay CG17 is held up, relay 20CS first drops followed by relay 17CS at the

end of its half-second release interval. Relay CG17, however, drops to complete the circuit of transformer TTE prior to relay 15CS dropping at the end of its half-second release interval, so that when relay TRF picks up due to the on period of current following the 3½ second off period, code registering relay 17CR picks up over a circuit substantially corresponding to the circuit previously traced for relay 20CR but in which front contact 140 of relay 17CS is open so that relay 20CR is deenergized, and back contact 142 of relay 17CS is closed so that relay 17CR is energized.

Relay 20CS also picks up to energize relay C1R, and relay C1R in turn picks up to open the circuits of relays 20CS and 17CR. Relay 17CR remains up, however, since all detecting relays CR are provided with slow releasing periods of approximately 12 seconds, and relay 20CS also remains up due to its 3 second release interval. When the coding apparatus at end E of the section cyclically repeats the coding of current at the 20-17 code rate, relays 20CR and 17CR are alternately energized when relay TRF responds to "on" periods of code separated by "off" periods having a duration alternately of 3 seconds and 3½ seconds, and these relays therefore indicate that relay TRF is responding to a composite code comprising the 20 and 17 code rates.

In the event that relay TRF responds to a code involving the 15 code rate wherein an on period is followed by an off period having a duration of four seconds, then relays 20CS, 17CS and 15CS all release during the 4 second off interval, and during the next succeeding on period relay 15CR becomes energized over a circuit similar to the circuit previously mentioned for relay 20CR but in which back contact 143 of relay 15CS is closed to connect the winding of relay 15CR to the circuit. The energization of relay 15CR indicates that relay TRF is responding to a code including the 15 code rate. It follows, therefore, that relays 20CR, 17CR and 15CR detect the different relatively low rates at which energy is coded by the code generating relays CG.

In a modified arrangement of the code detecting apparatus, shown in Fig. 3, the code registering relays CR are provided with slow releasing repeater relays CRP so arranged as to be selectively energized in accordance with the energization of the associated code registering relays. The slow releasing characteristics of the repeater relays are selected so that substantially a 12 second control interval may be provided for each code registering relay although such relays themselves have only, say, 6 second release intervals. To effect such 12 second control intervals, a plurality of slow releasing relays are employed one to detect each individual code rate of each combination of relatively low code rates. Referring to Fig. 3, the slow releasing repeater relay 1CRP is provided with an energizing circuit extending from terminal B through front contact 150 of relay 20CR, front contact 151 of relay 17CR and the winding of relay 1CRP to terminal C, hence relay 1CRP is energized whenever relays 20CR and 17CR are picked up in response to a combination 20-17 code. Relay 1CRP controls the control circuit governed by the associated code detecting relay 20CR and, as indicated, has a front contact 152 which may be connected in an alternate circuit path around front contact 144 of relay 20CR in the obvious energizing circuit of approach relay AR1 of Fig.

2b. Relay 2CRP is energized over a circuit extending from terminal B through front contact 153 of relay 17CR, front contact 154 of relay 20CR, and the winding of relay 2CRP to terminal C, and hence is energized when relays 20CR and 17CR respond to a combined 20-17 code. Relay 2CRP controls a contact 155 which may be employed in aiding relay 17CR in the control of associated apparatus, such as lock magnet M1 of Fig. 2b. Relay 3CRP is provided with a circuit including front contacts 150 and 156 of relays 20CR and 15CR, respectively, and thus detects a 20-15 code combination; relay 4CRP is picked up over a circuit including front contacts 157 and 158 of relays 15CR and 20CR, respectively, and also detects a 20-15 code; relay 5CRP is energized over a circuit including front contacts 153 and 159 of relays 17CR and 15CR, respectively, and thus detects a 17-15 code combination; while relay 6CRP is energized over front contacts 157 and 160 of relays 15CR and 17CR, respectively, and also detects a 17-15 code combination. Each of these relays when energized controls contacts which may be interposed in the control circuits governed by relays 15CR, 17CR and 20CR, respectively, of Fig. 2b.

It follows that by providing relays CR with slow releasing repeater relays CRP, the slow releasing relays 20CR, 17CR and 15CR might release due to relatively long intervals between successive pulses of the codes detected by such relays, without effecting the control established by such relays since the slow releasing repeater relays will remain up. In this manner, the slow release intervals of relays CR of Fig. 2b may be decreased.

As shown in Fig. 2, relays 20CR and 17CR are picked up to indicate that relay TRF is following 100 cycle current coded at the combined 20 and 17 code rates. Approach relay AR1 accordingly is energized over a circuit including front contact 144 of relay 20CR, thereby causing approach indicator AKF to be illuminated, and lock magnet M1 is energized over a circuit including front contact 145 of relay 17CR, contacts 11-12 of circuit controllers J2F and J1F, respectively, front contact 57 of approach relay AR1 and the winding of magnet M1 to terminal C. Indicator KF also is illuminated over a circuit including front contacts 147 and 146 of relays 17CR and 20CR, respectively.

If a train is to be moved on stretch X from tower Q to tower P, the operator at tower Q indicates the proposed traffic movement by depressing push button PB1, thereby changing the coding of the 200 cycle current supplied to the rails at end F of section E-F from the 180 to the 20 code rate. Relay TRE thereupon responds to this 20 coded current, and relays HE and AJE drop, thereby deenergizing relay AR2, lever lock magnet M2, and indicator AKE. Indicator VKE also becomes energized over an obvious circuit including back contact 165 of relay HE and front contact 166 of relay BSA, thereby indicating that a west-bound train movement from tower Q to tower P is proposed.

If conditions at tower P are favorable for a westbound movement, the operator at tower P may indicate such favorable conditions by depressing push button PB2 or by reversing lever V1. For example, if push button PB2 is depressed, the coding of the 100 cycle current supplied to section E-F is changed from the 20-17 combination code to a 20-17-15 code combination, as explained heretofore, and relay TRF re-

sponds to this code to cause code detecting relays 20CR, 17CR and 15CR to be picked up. When relay 15CR picks up, its front contact 149 closes to complete an obvious circuit for indication lamp VKF, which accordingly becomes illuminated to indicate that the operator at tower P consents to a westbound move. The operator at tower Q may now release push button PB1, thereby restoring the coding of the 200 cycle current to the 180 code rate, whereupon relays AJE and HE at the other end of the section pick up and indication lamp VKE goes out.

The operator at tower Q may now operate westbound traffic lever V4 to its reverse position, thereby interrupting at contact 83 the supply of current to the supplemental decoding apparatus associated with relay TRF, and closing contact 81 to condition decoding transformer DTF to be energized and thus condition relays AJF, BJF and HF for operation. The operator at tower Q may also move signal lever V2 to its reverse position, thereby locking lever V4 in its reverse position and lever V3 in its normal position. When indication lamp VKE at tower P becomes dark due to the release of push button PB1 at tower Q, the operator at tower P may reverse westbound traffic lever V1, thereby opening contact 100 to deenergize the code generating relays CG, opening contact 99 to disconnect the 100 cycle current from the track rails, and closing contact 168 to connect the 100 cycle current to the track rails of section E-F over one contact or another of coder CTE. If, for example, conditions at tower P are such that signal WSE may be operated to clear or caution, the operator may move lever V5 to operate signal ESE from its stop position, and contact 13-15 of controller J1E operated by signal WSE closes to complete a circuit for transformer TTE, this circuit extending from one terminal of winding 23 of line transformer LTE through condenser 24, lever contact 168 of lever V7, contact 180 of coder CTE, contact 15-13 of circuit controller J1E, contacts 169 and 170 of lever V7, contact 99 of lever V8, winding 25 of transformer TTE and common connection CC to the other terminal of winding 23 of line transformer LTE. However, if the operator at tower P keeps signal WSE at stop, then contact 13-14 of controller J1E is closed and the 75 code contact of coder CTE is effective to code the current supplied to transformer TTE, as is readily apparent from an inspection of the drawings.

Relay TRF responds to this 100 cycle current and picks up relay HF, or relays HF and AJF, according as the current is coded at the 75 or 180 code rates, and signal WSF accordingly is caused, with contact 174 of lever V2 closed, to display its caution indication if only relay HF is picked up due to relay TRF following 75 code, or its clear indication if both relays HF and AJF are picked up due to relay TRF following 180 code.

With signal WSF at either its caution or clear condition, the apparatus is conditioned to permit a movement on track X from tower Q to tower P. When the train enters the limits of section F-G, relay TRG of course is released and drops to open its front contact 92 and thereby interrupt the circuit connection of the 200 cycle current source to the rails at end F of section E-F. Relay TRE at the opposite end of the section accordingly becomes deenergized, and all decoding relays associated therewith release so that approach relay AR2, lock magnet M2 and indication lamp AKE also become deenergized, 75

and indication lamp KE becomes energized. If, now, lever V5 is in its reverse position, the approach locking of the lever is rendered effective since with magnet M2 deenergized, the lever cannot be restored to its full normal position unless the time release device TDE associated with lever V5 is actuated, as pointed out heretofore in connection with the operation of the apparatus of Fig. 1.

10 When the train occupies section E-F, signal WSF of course goes to stop since relay TRF is shunted and the associated decoding relays are released. When the train occupies section D-E and shunts relay TRD, back contacts 59 and 60 of relay TRD close to complete the previously mentioned track circuit release circuit of relay AR2, thereby unlocking lever V5. Signal lever V2 may be restored to normal, and traffic levers V4 and V7 may also be restored to normal so that when the train vacates section E-F, the apparatus is restored to its normal condition.

It is, of course, to be understood that modifications in the apparatus just described may be utilized to provide both indications and proposed traffic movements and traffic locking. For example, if indicator VKE at tower P becomes illuminated to indicate a proposed westbound train movement, the operator at tower P may respond by merely moving eastbound traffic lever V1 to its reverse position, thereby deenergizing at contact 100 the code generating relays CG, interrupting at contact 99 the connection of the 100 cycle source to the track rails through contacts of the code generating relays CG, and closing contact 168 to connect this source to the rails through one contact or another of coder CTE.

Relay TRF accordingly responds to the relatively rapid coding of the 100 cycle current, but the decoding relays CS and the code detecting relays CR are non-responsive to such code rate so that relays 17CR and 20CR drop and indication lamps KF and AKF become dark. The operator at tower Q may now reverse lever V4, thereby supplying energy over contact 81 and contact member 84 of relay TRF to decoding transformer DTF, and decoding relays AJF, BJF and HF accordingly are conditioned to pick up in accordance with the code rate of the received current. Signal lever V2 then may be operated to control signal WSF and permit a westbound movement.

In a further modification, the source of current at tower Q may be connected directly to contact member 84 of relay TRF interposed in the energizing circuit of decoding transformer DTF and not, as shown, be taken through contact 80 or 81 of levers V3 and V4, respectively. In such event, the decoding transformer DTF would normally be energized when current coded at the relatively low code rates of 20, 17 or 15 codes is received, but relays HF, BJF and AJF are non-responsive to such code rates and hence are normally deenergized. However, when lever V7 at tower P is reversed to acknowledge and permit a westbound move, then the increased rates of coding will cause relays HF, BJF and AJF to respond and pick up, and signal control lever V2 may be operated to control signal WSF to its caution or clear condition in accordance with the code rate of the received current. Traffic lever V4 would normally be provided, however, and interlocked with lever V2 so that the latter lever could not be operated to its reverse position unless traffic lever V4 is first reversed.

If, now, with the apparatus of Fig. 2 in its

normal condition as illustrated in the drawings, the operator at tower P wishes to send an eastbound train on track X toward tower Q, he may indicate the proposed traffic movement by depressing push button PB2, thereby altering the coding of the 100 cycle current from the combination 20-17 code to the 20-17-15 code, as pointed out previously, and causing relay 15CR at tower Q to pick up and illuminate indication lamp VKF. If conditions are favorable for an eastbound traffic movement, the operator at station Q may depress push button PBI to alter the coding of the 200 cycle current from the 180 code rate to the 20 code rate, thereby deenergizing relays AJE and HE at tower P and causing indication lamp VKE to become illuminated to indicate that tower Q may receive the train. The operator at tower P may now operate lever V8 to its reverse position, thereby opening contact 101 to deenergize the code generating relays CG, opening contact 99 to disconnect from transformer TTE the 100 cycle source, and opening contact 85 and closing contact 86 to shift the tuning of relay TRE from the 200 cycle current to the 100 cycle current. Contacts 172 and 173 of lever V8 also close so that 200 cycle current is supplied to transformer TTE over one contact 120 or another contact 180 of coder CTE according as signal ESE is in its clear position or is in either its caution or stop position. When signal ESE is in either its stop position, as shown, or its caution position, contact 17-16 of controller J3E controlled thereby is closed, and 200 cycle current coded at the 180 code rate is supplied to transformer TTE over a circuit extending from winding 42 of frequency changer FC through condenser 43, contact 172 of lever V8, contact 180 of coder CTE, contact 17-16 of controller J3E, front contact 176 of relay TRD, contact 171 of lever V1, contact 173 of lever V8 and winding 25 of transformer TTE. If, however, signal ESE is cleared, then contact 18-16 of controller J3E closes and contact 120 replaces contact 180 of coder CTE in the just traced circuit.

This 200 cycle current supplied to section E-F is of course ineffective to operate relay TRF, and relay TRF drops so that all of the decoding relays associated therewith are released with the result that relay AR1 also releases and indicators KF and AKF become dark. When this happens, the operator at tower Q may reverse his eastbound traffic lever V3, thereby opening contacts 89 and 93 to disconnect the 200 cycle source from transformer TTF, opening contact 87 and closing contact 88 to shift the tuning of relay TRF from the 100 cycle to the 200 cycle source, and closing contacts 90 and 175 to connect the 100 cycle source to transformer TTF over one contact or another of coder CTF. Relay TRF accordingly responds to the 200 cycle current received from the rails of section E-F and conditions relay HF and either relay BJF or AJF to be picked up, thereby energizing indicator KF, relay AR1, and causing indicator AKF to be energized. Lever V1 may now be reversed to close its contact 181, whereupon signal ESF clears. Relay TRE responds to the 100 cycle current received from the rails of section E-F to condition relays BSA, FSA, HE and AJE to be picked up according to the code rates at which the 100 cycle current is coded by coder CTF, this code selection being determined by the position of signal ESE. Signal lever V5 at tower P may now be operated to its reverse position to close its contact 182 and the signal will go to caution or clear according as

signal ESF is at stop, or is in its caution or clear position, respectively, to cause the 100 cycle current to be coded at the 75 or the 180 code rate.

The eastbound train accordingly is permitted to move from tower P to tower Q, it being noted that 100 cycle current is fed toward the train from the opposite end F of the section so that it is possible to control train-carried apparatus on the train by this 100 cycle current.

10 Lever V5 at tower Q is approach locked when the westbound train enters section D-E and relay TRD drops to disconnect the 200 cycle current from the track rails, this locking being attained in a manner explained in detail heretofore.

15 Signal ESE goes to stop when the train occupies section E-F to shunt relay TRE, and the apparatus may be restored to normal after the train vacates section E-F by restoring signal lever V5 and traffic levers V8 and V3 to their respective normal positions.

20 From the foregoing description, it is readily apparent that apparatus embodying my invention provides means whereby traffic locking between towers may be effected without the use of line wires by utilizing the track rails as transmission conductors. In addition, it is apparent that approach locking of traffic controlling functions is effected without line wires. Furthermore, the apparatus incorporates means whereby track circuit current of the usual 100 cycle frequency is supplied to the stretch toward a train irrespective of the direction of its movement, thereby enabling train-carried apparatus on the train to be controlled.

25 30 35 40 45 Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. In combination, a stretch of railway track including an insulated track section, two signals one at either end of said section for governing traffic over said stretch in a given direction, a manually operable member controlling one of said signals, means governed by said one signal for controlling the supply of current of a particular character transmitted from a source at said one end of said section to said other end wholly over a track circuit comprising the rails of said section, means controlled by said particularly characterized track circuit current for controlling the other of said signals, means governed by said other signal for controlling the supply of current of another distinctive character transmitted from a source at said other end of said section to said one end wholly over a track circuit comprising the rails of said section, locking means for said manually operable member, and means controlled by said other distinctively characterized track circuit current for controlling said locking means.

2. In combination, a stretch of railway track including an insulated track section, two signals one at either end of said section for governing traffic in a given direction over said stretch, two sources of current having distinctively different characteristics one source at one end of the section and the other source at the other end, a manually operable member controlling the signal at said one end of said section, means controlled by said one signal for controlling the

supply of current transmitted from said one source to the other end of said section wholly over a first track circuit comprising the rails of said section, means controlled by said first track circuit current for controlling the other of said signals, means controlled by said other signal for controlling the supply of current transmitted from said other source to the one end of said section wholly over a second track circuit comprising the rails of said section, means controlled by said second track circuit current, and locking means for said manually operable member controlled by said last-mentioned means.

3. In combination, a stretch of railway track including an insulated track section, two signals one at either end of said section for governing traffic in a given direction over said stretch, two sources of current having distinctively different characteristics one source at one end of the section and the other source at the other end, a manually operable member for controlling the signal at said one end of said section, locking means for said member, means controlled by said one signal for controlling the supply of current transmitted from said one source at said one end to the other end of said section wholly over a first track circuit comprising the rails of said section, means controlled by said first track circuit current for controlling the other of said signals, means governed by said other signal for controlling the supply of current transmitted from said other source at said other end to the one end of said section wholly over a second track circuit comprising the rails of said section, and means controlled by said second track circuit current for controlling said locking means, whereby said locking means is rendered effective to lock said member unless said other signal occupies a proper restrictive position.

4. In combination, a stretch of railway track including an insulated track section, two signals one at either end of said section for governing traffic in a given direction over said stretch, two sources of current having distinctively different characteristics one source at one end of the section and the other source at the other end, a manually operable member for controlling the signal at said one end of said section, locking means for said member, means controlled by said one signal for controlling the supply of current transmitted from said one source at said one end to the other end of said section wholly over a first track circuit comprising the rails of said section, means controlled by said first track circuit current for controlling the other of said signals, means controlled by said other signal for controlling the supply of current transmitted from said other source at said other end to the one end of said section wholly over a second track circuit comprising the rails of said section, means controlled by said second track circuit current for controlling said locking means, and other means for controlling said locking means and governed by a time delay mechanism effective to impose a time delay in the control of said locking means.

5. In combination, a stretch of railway track divided into an advance and a rear track section, two signals one at either end of said advance section for governing traffic over said stretch from said rear section, a manually operable member for controlling the one signal at the exit end of said advance section, locking means for said member and effective when said one signal is cleared, control means for operating the other of said signals, means governed by said one signal for controlling said control

means by current transmitted from a source at said exit end to said entrance end wholly over a track circuit comprising the rails of said advance section, means for controlling said locking means by current transmitted from another source at said entrance end to said exit end wholly over a track circuit comprising the rails of said advance section and governed by said other signal to be effective to release said member only if said other signal occupies a proper restrictive position, and means governed by traffic in said rear section for rendering said lock controlling means ineffective to release said member irrespective of the position of said other signals.

6. In combination, a stretch of railway track divided into an advance and a rear track section, two signals one at either end of said advance section for governing traffic over said stretch from said rear section, a manually operable member for controlling the one signal at the exit end of said advance section, locking means for said member and effective when said one signal is cleared, control means for operating the other of said signals, means governed by said one signal for controlling said control means by current transmitted from a source at said exit end to said entrance end wholly over a track circuit comprising the rails of said advance section, means for controlling said locking means by current transmitted from another source at said entrance end to said exit end wholly over a track circuit comprising the rails of said section and governed by said other signal to be effective to release said member only if said other signal occupies a proper restrictive position, means governed by traffic in said advance section for rendering said lock controlling means ineffective to release said member irrespective of the position of said other signal, and means responsive to traffic in said rear section for approach energizing said one signal.

7. In combination, a stretch of railway track divided into an advance and a rear track section, two signals one at either end of said advance section for governing traffic over said stretch from said rear section, a manually operable member for controlling the one signal at the exit end of said advance section, locking means for said member and effective when said one signal is cleared, control means for operating the other of said signals, means governed by said one signal for controlling said control means by current transmitted from a source at said exit end to said entrance end wholly over a track circuit comprising the rails of said advance section, means for controlling said locking means by current transmitted from another source at said entrance end to said exit end wholly over a track circuit comprising the rails of said section and governed by said other signal to be effective to release said member only if said other signal occupies a proper restrictive position and additionally governed by traffic in said advance section for rendering said lock controlling means ineffective to release said member irrespective of the position of said other signal, and other means for controlling said locking means to release said member and effective at the end of a predetermined time delay interval.

8. In combination, a stretch of railway track including an insulated track section, signals at each end of said section governing traffic movements in one direction over said stretch, manually operable means for controlling the signal

at the exit end of said section, two sources of distinctively characterized current one at each end of said section, means governed by said exit end signal for supplying to the rails at the exit end of said section current from one of said sources coded at one code rate or another in accordance with the position of said exit end signal, means receiving energy from the rails at the entrance end of said section and selectively responsive to current from said one source for controlling the signal at said entrance end in accordance with the code rate of the received current, means governed by said entrance end signal for supplying to the rails at said entrance end of said section current from the other of said sources coded at one code rate or another in accordance with the position of said entrance end signal, other means receiving energy from the rails at said exit end of said section and selectively responsive to current from said other source, and lock means for said manually operable means controlled by said other means for preventing a movement of said manually operable means when said entrance end signal occupies a predetermined position as indicated by said other means responding to current from said other source coded at a particular one of said code rates.

9. In combination, a stretch of railway track including a track section, two signals governing traffic in one direction over said stretch and positioned respectively at opposite ends of said section, a first source of alternating current at the exit end of said section, a second source of alternating current at the entrance end of said section having a frequency different from the frequency of said first source, a track relay at each end of said section responsive only to current of the frequency supplied at the opposite end of said section, means governed by the signal at the exit end of said section for supplying current from said one source to the rails at said exit end of said section coded at one or another of a plurality of code rates in accordance with the position of said exit end signal, means responsive to the code rate of operation of the track relay at said entrance end for controlling the position of the other of said signals, means controlled by said other signal for supplying current from said other source to the rails at said entrance end of said section coded at one or another of said plurality of code rates in accordance with the position of said other signal, a manually operable lever for controlling the position of said one signal, and lock means for said lever controlled by the track relay at said exit end of said section.

10. In combination, a stretch of railway track including a track section, two signals governing traffic in one direction over said stretch and positioned respectively at opposite ends of said section, a first source of alternating current at the exit end of said section, a second source of alternating current at the entrance end of said section having a frequency different from the frequency of said first source, a track relay at each end of said section responsive only to current of the frequency supplied at the opposite end of said section, means governed by the signal at the exit end of said section for supplying current from said one source to the rails at said exit end of said section coded at one or another of a plurality of code rates in accordance with the position of said exit end signal, means responsive to the code rate of operation of the track relay at

5 said entrance end for controlling the position of the other of said signals, means controlled by traffic conditions in the rear of said other signal and by said other signal for supplying current from said other source to the rails at said entrance end of said section coded at one or another of said plurality of code rates in accordance with the position of said other signal, a manually operable lever for controlling the position of said one signal, code responsive means controlled by the track relay at said exit end of said section, and lock means for said lever controlled by said code responsive means.

11. In combination, a stretch of railway track, 15 two signals at each end of said stretch one for governing traffic in one direction and the other for governing traffic in the opposite direction, a first manually operable control means at one end of said stretch for establishing control of the 20 signals governing traffic in said one direction and a second manually operable means at the other end of said stretch for establishing control of the signals governing traffic in said opposite direction, a first control means at said other end 25 of said stretch for controlling the operation of the signal governing traffic in said one direction at said other end, other control means at said one end of said stretch for controlling the operation of the signal governing traffic in said opposite direction at said one end, means controlled by said first manually operable control means for controlling said first control means by current transmitted from said one to said other end of said stretch wholly through a track circuit comprising the rails of said stretch, and means controlled by said second manually operable control 35 means for controlling said other control means by current transmitted from said other to said one end of said stretch wholly through a track circuit including the rails of said stretch.

12. In combination, a stretch of railway track, 40 two signals at each end of said stretch for governing traffic in opposite directions, one signal at each end being a rear signal governing traffic 45 in said stretch and the other signal being an advance signal, a first control means at one end of said stretch for establishing control of the rear signal at said one end and its associated advance signal, a second control means at the other end of said stretch for establishing control over the rear signal at said other end and its associated advance signal, two track circuits for said stretch 50 a first comprising a first source of distinctively characterized current at said one end and a first track relay at said other end uniquely responsive to said distinctively characterized current and the second comprising a second source of differently characterized current at said other end and a second track relay at said one end uniquely responsive to said differently characterized current, means governed by said first control means and other means governed by the advance signal at 55 said one end for controlling the energization of said one track circuit by said first source, means governed by said first track relay for controlling the advance and rear signals at said other end of said section, means governed by said second control means and other means governed by the 60 advance signal at said other end for controlling the energization of said second track relay by said second source, and means governed by said second track relay for controlling said advance and rear signals at said one end of said stretch.
